UNITED STATES PATENT OFFICE.

FRANCIS F. MOTLEY, OF NEW HAVEN, CONNECTICUT, ASSIGNOR TO
REYNOLDS & CO., OF SAME PLACE.

SCREW-MACHINE.

SPECIFICATION forming part of Letters Patent No. 289,125, dated November 27, 1883.

Application filed May 31, 1883. (Model.)

To all whom it may concern:

Be it known that I, FRANCIS F. MOTLEY, of New Haven, in the county of New Haven and State of Connecticut, have invented a new Improvement in Screw-Machines; and I do hereby declare the following, when taken in connection with accompanying drawings and the letters of reference marked thereon, to be a full, clear, and exact description of the same, and which said drawings constitute part of this specification, and represent, in—

Figure 1, a top or plan view; Fig. 2, a front view; Fig. 3, a rear view; Fig. 4, a partial top view, portions removed to show the clutch mechanism; Figs. 5, 6, 7, and 8, detached views enlarged; Fig. 9, a transverse section on line *x* *x*, looking toward the mandrel; Fig. 10, a transverse section on line *z* *z*, looking toward the mandrel.

This invention relates to an improvement in that class of screw-making machines designed for producing what are commonly called "fine-thread" or "machine" screws—that is to say, screws which are cut in a substantially solid die, whereby the uniformity of thread necessary for metal work is acquired, and particularly to that class in which the mechanism operates automatically to first run the die onto the blank to thread it, then reverse it and run it off preparatory to the presentation of a new or unthreaded blank, the object of the invention being to give to the die the necessary lead for it to properly engage the blank, so that the thread cut by the die will be sufficient to draw the die onto the blank, and also to reverse the rotation of the die at a positive predetermined time; and the invention consists in the construction, as hereinafter described, and more particularly recited in the claims.

In illustrating my invention I show only the mechanism in connection with the die. The part of the machine which presents and holds the blank may be any of the common or usual constructions, immaterial to this invention, further than that the blank shall be properly presented and held concentric with the revolving screw-cutting die.

A is the driving-shaft, arranged in bearings B, and to which power is applied through a

pulley, C, or otherwise, to give it a constant rotation in one direction.

D is the mandrel, supported in bearings E, free for rotation, and also for longitudinal movement. At its forward end it carries the screw-cutting die a, and stands in axial line with the blank b when presented to be cut. On the mandrel are two loose gears, F and G. Into the one, F, a gear, H, on the driving-shaft works, and into the other, G, a gear, I, on the driving-shaft works through an intermediate gear, K, and so that the one gear, F, turns in one (the forward) direction, while the gear G turns in the opposite direction under the constant forward direction of the driving-shaft. Between the two gears F G is a clutch-sleeve, L, which, when moved forward, as in Fig. 4, engages the gear F and is free from the gear G; but when moved to the extreme opposite direction it engages the gear G and is free from the gear F. This clutch-sleeve L is splined to the mandrel in the usual manner for such clutches, and so that the one gear, F, engaging the clutch will turn the mandrel forward, and engaged with the gear G will turn the mandrel backward, or an intermediate position will leave the sleeve free from the influence of either gear.

M is a sliding bar, arranged to move parallel with the mandrel, and from this bar M an arm, N, extends into an annular groove in the clutch-sleeve L, as seen in Fig. 4, so that as the bar M is moved in either direction it will communicate a corresponding movement to the clutch L. To the bar M a spring, P, is applied, the action of which is to draw the clutch from its engagement with the gear F and into engagement with the gear G; but when the slide M is moved to bring the clutch into engagement with the gear F a latch, R, pivoted on the frame, engages a shoulder, S, on the slide, as seen in Fig. 5, and holds the slide in that forward or engaged position—that is, in position to turn the screw-cutting die in the forward or cutting direction.

From the latch R an arm, T, extends upward, and in the path of a trip, U, extending from a horizontal sliding bar, V. This sliding bar is arranged, preferably, directly over the mandrel, as shown, and to the bar a longitudi-

95

100

nal movement is communicated, corresponding to the movement of the mandrel. This movement is produced by a disk, Y, fixed to the mandrel and revolving with it, and which works in a corresponding groove in the under side of the bar V, as seen in Fig. 3, and so that as the mandrel passes onto the blank in cutting its thread it draws the trip U toward the arm T of the latch, and when the trip strikes that arm T it turns the latch, so that it will escape from the shoulder S, as seen in broken lines, Fig. 5, just as the cutting of the thread is completed. Instantly upon the escape of the latch R from the shoulder S the spring P acts upon the slide M and draws the clutch from the gear F and throws it into engagement with the gear G, which is revolving in the opposite direction, and which opposite revolution is immediately imparted to the mandrel, causing it to revolve in the opposite direction and run back from the blank upon which it has cut the thread. To throw the clutch in the opposite direction and into engagement with the gear F when a new blank shall have been presented, I arrange a shaft, d, in axial line with the driving-shaft, in bearings e, which has an intermittent rotation imparted to it from the driving-shaft in the following manner:

At the forward end of the driving-shaft is a disk, f. (Shown enlarged in Fig. 6.) On the corresponding end of the shaft d is a disk, g, which is constructed with an annular groove, h. Through the disk g, and transversely across the groove h, is a bolt, i, against which a spring, l, bears, the tendency of which is to force the bolt toward the disk f; and when a corresponding recess, m, stands in line with the bolt the spring will force the bolt into the said recess and engage the two disks, so that the constant revolution of the disk f will be imparted to the disk g and the shaft which carries it; but when the bolt is withdrawn from engagement with the disk f, then the shaft d is stationary, while the driving-shaft continues its revolution.

o are two arms of a lever hung upon a pivot, r, the end of one arm, n, standing in the groove h of the disk g, the other extending over the sliding bar V. (Seen enlarged in Fig. 7.) To the arm o a spring, t, is applied, the tendency of which is to lift the arm n in the groove h; but when the arm n is depressed, as seen in Fig. 7, it rests against a shoulder, u, on the bolt i, as seen in Fig. 6, and holds the bolt out of engagement with the disk f. As the mandrel is advancing and cutting the thread the arm o of this lever rests on a plate, w, on the top of the bar V, as seen in Fig. 7, and there remains until the return of the mandrel, as before described, and just as the return of the mandrel in withdrawing the die from the blank has been completed the arm o escapes from the plate w, as seen in Fig. 3, and drops upon the bar V, which raises the other end, n, as indicated in broken lines, Fig. 6, so as to escape from the shoulder u of the bolt, and permit that bolt to spring into engagement

with the disk f, and from the time of such engagement of the bolt the disk g and its shaft will revolve with the driving-shaft, the bolt passing around with the disk. After the bolt has escaped and passed from the arm n of the lever, then a cam, 3, on the disk g strikes an arm, 4, which extends down from the arm n to the opposite side of the disk, and forces the said arm downward, drawing with it the arm n into the path of the then advancing bolt, and as the rotation of the disk continues the shoulder u will strike an incline, 5, on that side of the arm n, as seen in Fig. 8, which incline 80 will force the bolt out of engagement with the disk f, and there hold it until such time as the lever shall be again released. During the rotation of the shaft d, thus imparted, a cam, 6, on the said shaft d strikes a lever, 7, which 85 extends up from the rock-shaft 8, and from which rock-shaft another arm, 9, extends up into engagement with the bar M, and so that the movement of the rock-shaft by said cam 6 draws the bar M forward and takes the clutch 90 from engagement with the gear G and into engagement with the gear F, expands the spring P, and brings the latch into engagement to hold the bar M, as before described, and as the mandrel starts forward it brings the plate 95 w on the slide V beneath the arm o of the lever, as seen in Fig. 7, and so as to hold that arm, o, up and the other arm, n, down into the groove h, and therefore prevent the engagement of the bolt i with the disk f, and from the time of such disengagement of the bolt i until its re-engagement, as before described, the shaft d remains stationary.

To give a lead to the mandrel, and so that the die will run onto the blank to engage it to such an extent that the screw itself may act as the feed to draw the die onto the blank, a sliding bar, 10, is arranged beneath or parallel with the bar M. This slide extends to the rear and turns at right angles, forming an arm, 11, in rear of the mandrel, as seen in Fig. 4. The bar extends forward and is connected to the upper end of an arm, 12, extending up from a rock-shaft, 13. From this rock-shaft another arm, 14, extends up into the path of a cam, 15. 115 On the shaft d, and so that when the said shaft d rotates, as before described, the cam 15 will turn the rock-shaft 13 forward and bring the arm 11 against the end of the mandrel D and press it forward toward the blank at a rate of movement corresponding to the pitch of the thread, and so that the die in the mandrel will be forced onto the blank and start the thread. Then, just before the rotation of the shaft d ceases, the arm 14 escapes from the cam 15, and the bar 10 returns by the action of the spring 20, leaving the mandrel free to run onto the blank under the engagement which it is thus forced to make, the thread which the die cuts being sufficient to draw the die onto 120 the blank. By this construction the backward and forward movement of the mandrel carrying the die is made automatic and positive—that is to say, it advances to a certain prede-

terminated point, and is there compelled to return, and cannot advance beyond that point or stop short of it—a difficulty experienced in this class of machines where the arrest of the advance movement of the cutting-die depends upon a spring or other uncertain devices.

Instead of employing the bar V to trip the latch R, which holds the bar M, the disk Y or a collar on the mandrel may operate directly upon the latch without the intervention of the bar V.

I claim—

1. In a screw-cutting machine substantially such as described, the combination of a revolving mandrel carrying the screw-cutting die, two gears loose on said mandrel, a driving-shaft carrying corresponding fixed gears, with an intermediate gear between one of the gears on the driving-shaft and one of the gears on the mandrel, a clutch splined on the mandrel and arranged to engage either of said loose gears thereon, according to the direction the mandrel is to be turned, an auxiliary shaft in axial line with the driving-shaft, and a mechanism, substantially such as described, between said driving-shaft and said auxiliary shaft, whereby at a predetermined time said auxiliary shaft is coupled with or released from the driving-shaft, a sliding bar carrying an arm in connection with the clutch-sleeve on the mandrel, and a cam on said auxiliary shaft arranged to impart longitudinal movement to said sliding bar, to connect the clutch on the mandrel with one of the said loose gears, a latch to engage said bar when the clutch is so engaged, and a spring to throw the clutch out of the engagement so made and into engagement with the other loose gear on the mandrel when the latch which holds the bar shall have been tripped, substantially as described.

2. In a screw-cutting machine substantially such as described, the combination of the mandrel carrying the screw-cutting die, two gears loose on said mandrel, one running in one direction and the other in the opposite direction, a clutch-sleeve splined to the mandrel between said two gears, a sliding bar carrying an arm in connection with said clutch-sleeve, and mechanism for imparting to said sliding bar a positive longitudinal movement in one direction, a latch to engage said bar when so moved, and a collar on the mandrel operating to trip said latch when the cutting of the screw shall have been completed, substantially as specified.

3. In a screw-cutting machine substantially such as described, the combination of the mandrel D, the loose gears F and G thereon, clutch-sleeve L, sliding bar M, arm N, latch R, sliding bar V, disk Y, and arm U, extending from said bar V, substantially as described.

4. In a screw-cutting machine substantially such as described, the combination of the mandrel carrying the screw-cutting die, and arranged to revolve in opposite directions, a driving-shaft arranged to so communicate

power to the said mandrel and auxiliary shaft in axial line with said driving-shaft, disk f on the driving-shaft, corresponding disk g on said auxiliary shaft, constructed with an annular groove, h, the bolt i, lever n o, the sliding bar V, in connection with the mandrel, the cam 3 on said auxiliary shaft, arranged to bear upon an arm, 4, extending from said lever n o, cam 6, rock-shaft 8, sliding bar M, in connection with said rock-shaft, and also in connection with the clutch-sleeve splined to the mandrel between the said two gears on the mandrel, and a latch, R, substantially as and for the purpose described.

5. In a screw-cutting machine substantially such as described, the combination of the mandrel carrying the screw-cutting die, the driving-shaft parallel therewith, and arranged to communicate revolution to said mandrel in either direction, an auxiliary shaft in axial line with the driving-shaft, and mechanism, substantially such as described, to connect said auxiliary shaft with said driving-shaft and release it therefrom at predetermined times, and a cam on the said auxiliary shaft, with mechanism, substantially such as described, between said cam and the wheels on the mandrel, through which the power is communicated thereto, whereby the rotation of said mandrel will be reversed at such predetermined times, substantially as described.

6. In a screw-cutting machine substantially such as described, the combination of the mandrel carrying the screw-cutting die, two loose gears on said mandrel working in opposite directions, a clutch-sleeve between said gears and splined to the mandrel, a cam operated by the driving-shaft at a predetermined time, and mechanism, substantially such as described, between said cam and said clutch, whereby a positive movement is imparted to said clutch in one direction, and a spring to impart movement to the clutch in the opposite direction, substantially as described.

7. In a screw-cutting machine substantially such as described, the combination of the mandrel carrying the screw-cutting die, two loose gears on said mandrel, working in opposite directions, a clutch-lever between said gears, splined to the mandrel, and a latch mechanism to lock said clutch with the gear, turning the mandrel in the forward or screw-cutting direction, and a trip, substantially such as described, to disengage said clutch when the screw-cutting is completed, substantially as described.

8. In a screw-cutting machine substantially such as described, the combination of the mandrel carrying the screw-cutting die, a driving-shaft arranged to communicate rotation to said mandrel in opposite directions, an auxiliary shaft in axial line with said driving-shaft, and mechanism, substantially such as described, to connect said driving-shaft to or disconnect it from said auxiliary shaft at a predetermined time, a cam on said auxiliary shaft, in connection with an arm in rear of said mandrel,

substantially as described, whereby the first advance of the mandrel carrying the die toward the blank to be cut is forced by said auxiliary shaft and released when the die has engaged the blank, substantially as described.

9. In a screw-cutting machine substantially such as described, the combination of the mandrel carrying the screw-cutting die, the driving-shaft arranged to communicate rotation to said mandrel in opposite directions, an auxiliary shaft in axial line with said driving-shaft, the driving-shaft carrying a disk, *f*, and the auxiliary shaft a corresponding disk, *g*, a sliding bolt, *i*, in said disk *g*, the lever *n o*, 15 sliding bar *V*, in connection with said mandrel, whereby said lever *n o* holds the bolt *i* from engagement with the disk on the driving-shaft until a predetermined time, when said bar releases said bolt from said lever and permits engagement of the auxiliary shaft with 20 the driving-shaft, a cam on said auxiliary

shaft, and mechanism, substantially such as described, between said cam and the mandrel, whereby said cam advances the mandrel to start the cutting of the blank, substantially as 25 described.

10. The combination of the driving-shaft provided with a disk, *f*, to revolve with it, an auxiliary shaft arranged in axial line with the driving-shaft, and carrying a disk, *g*, corresponding to the disk *f*, a bolt in said disk *g*, a lever arranged to permit the bolt to engage the driving-shaft, and a cam on said auxiliary shaft, arranged to turn said lever into a position to withdraw the bolt, whereby said auxiliary shaft is released from its connection with the driving-shaft, substantially as described. 30 35
